UNITED STATES PATENT OFFICE.

FRANK J. KAUFMANN, OF AMSTERDAM, NEW YORK, ASSIGNOR OF ONE-HALF TO
FREDERICK C. TRAUTMAN, OF AMSTERDAM, NEW YORK.

GLOVE-SEWING MACHINE.

1,145,148.

Specification of Letters Patent.

Patented July 6, 1915.

Application filed October 27, 1913. Serial No. 797,375.

To all whom it may concern:

Be it known that I, FRANK J. KAUFMANN, a citizen of the United States, residing at Amsterdam, county of Montgomery, and 5 State of New York, have invented certain new and useful Improvements in Glove-Sewing Machines, of which the following is a specification.

The invention relates to such improvements and consists in the novel construction and combination of parts hereinafter described and subsequently claimed.

Reference may be had to the accompanying drawings, and the reference characters 15 marked thereon, which form a part of this specification. Similar characters refer to similar parts in the several figures therein.

Figure 1 of the drawings is a top plan view of a glove-sewing machine provided 20 with my improved automatic thread-lock. Fig. 2 is a view partly in side elevation and partly in vertical section with the thread-lock open as when the machine is being operated to embroider or stitch a glove, the 25 sewing-mechanism being shown in the position occupied at the completion of the sewing operation preparatory to withdrawing the work from the machine. Fig. 3 is a view similar to Fig. 1, showing the thread-lock 30 closed and the slack thread taken up by the removal of the glove from between the feed-disks of the machine. Fig. 4 is a view similar to Fig. 1, illustrating the manner in 35 which the thread-lock is automatically opened by the initial forward movement of the needle-bar.

Certain features of the invention are applicable to various types of sewing-machines, but the invention is more particularly adapted 40 for glove-embroidering machines employed for ornamenting the backs of gloves.

The principal object of the invention is to prevent waste of the thread by the operation of withdrawing the work from the 45 machine. This object I accomplish by means of automatic thread-locking mechanism which is automatically locked upon the thread by the operation of releasing the work from the machine, and which is automatically unlocked to release the thread 50 when the machine is again started.

Referring to the drawings wherein the invention is shown in preferred form, 1 is the body of a well-known type of glove-sewing-machine wherein the work is clamped 55

by, and fed between, a pair of disks, 2 and 3, the disk, 2, having a rotative feed-motion and the disk, 3, being rotatively mounted upon the upper arm, 4, of an angle-lever fulcrumed at 5 upon the body of the 60 machine. The lower arm, 6, of said angle-lever is engaged by a spring, 7, which tends to hold the disk, 3, yieldingly against the disk, 2. The machine has the usual stitch-forming mechanism including a needle, 8, 65 carried by a reciprocating needle-bar, 9, and a looper, 10, the needle and looper being each supplied by a separate thread. The looper-thread, 11, passes from a guide-post, 12, through a tension, 13, and the needle-thread, 11^a, passes from a guide-post, 14, through a tension, 15, all in the usual manner.

The mechanism thus far described is common to such machines and is well understood 75 in the art, and it will not be necessary to further explain the same in detail.

In carrying out my invention I erect a spindle, 16, from a bracket, 17, which projects from the body of the machine at the 80 back thereof, and slidably mount upon said spindle a sleeve, 18, which rests upon a coil-spring, 19, tending to support the sleeve in an elevated position. Upon the upper arm of the post, 16, is mounted a cap, 20, having 85 a depending flange, 21, adapted to receive and closely fit the upper end of the sleeve, 18.

The spindle, 16, is provided with a transverse aperture, 22, adapted to freely receive the two threads, 11 and 11^a, and the sleeve, 90 18, is provided with similar apertures, 23, adapted to freely receive said threads and adapted in the lowermost position of the sleeve, 18, to register with the aperture, 22, in the spindle. When the apertures, 22 and 95 23, are in alinement with each other, the threads, 11 and 11^a, can pass freely therethrough to the sewing-mechanism, but, as will be seen from an inspection of Fig. 3, when the sleeve, 18, is permitted to be 100 forced upward by the spring, 19, the threads will be drawn upward with said sleeve between the wall of the sleeve and the inclosed spindle, 16, and between the wall of the sleeve and the inclosed flange, 21, on 105 the cap, 20, whereby the threads are wedged in between the spindle, 16, and flange, 21, of the cap, and are caused to change direction abruptly several times which effectively prevents any feeding-motion of the 110

thread through the lock when the sleeve, 18, is in its elevated position. During the sewing-operation the sleeve, 18, is detachably held in its lowermost position by means of a hook, 24, fulcrumed at 25, upon a bracket projecting from the body of the machine, and drawn toward the sleeve, 18, by means of a coil-spring, 26, causing the hook, 24, to automatically engage a shoulder or flange, 27, on the sleeve, 18, when the sleeve is sufficiently depressed. When the hook, 24, is interlocked with the shoulder, 27, as shown in Fig. 2, the sleeve, 18, will be held depressed so that the apertures, 23, in the sleeve are in line with the aperture, 22, in the spindle, 16, permitting the threads to feed freely.

The sleeve, 18, is automatically depressed to permit the hook, 24, to automatically interlock with the shoulder, 27, by means of a pair of cams, one of which, 28, is fixed upon the rear end of the reciprocatory needle-bar, 9, the other cam, 29, being fixed upon the sleeve, 18, in the path of the cam, 28, when the sleeve, 18, is elevated. The movement imparted to the cam, 28, by the forward movement of the needle-bar, 9, is sufficient to depress the cam, 29, and the sleeve, 18, to permit the hook, 24, to interlock with the shoulder, 27 on the sleeve.

The lower end, 30, of the hook-lever projects into the path of the lower arm, 6, by the angle-lever which carries the disk, 3, in position to be engaged and operated by the arm, 6, to release the hook, 24, from the shoulder, 27, when the arm, 4, is moved to separate the disks, 2-3, to permit the withdrawal of the work. It will thus be seen that the separation of the disks, 2-3, to release the work is automatically accompanied by the releasing of the sleeve, 18, to the action of the spring, 19, which instantly forces the sleeve upward to lock the thread as above described, and as shown in Fig. 3.

In order to leave sufficient slack in the thread which can be drawn out with the work and then severed therefrom to leave properly projecting ends which will not be withdrawn through the eyes of the needle and looper respectively, I locate between the thread-locking mechanism and the tensions, a yielding take-up in the form of a drop-spindle, 31, provided in its upper end with an eye, 32, to receive the threads, 11 and 11^a, which drop-spindle is adapted to rest during the sewing operation in a depressed position with its eye, 32, at a substantial distance below the level of the thread-receiving apertures in the guide-posts, 12 and 14, and the thread-locking mechanism. In the depressed position of the drop-spindle, 31, a downwardly extending loop or V-shaped stretch, 34, is formed in each thread which can be taken up as slack by pulling the threads out through

the needle and looper after the locking mechanism has become effective. The drop-spindle, 31, reciprocates vertically in a sleeve 33, mounted in fixed relation to the body of the machine, the spindle being guided in its movements by means of a pin, 35, which travels in a slot, 36, in the sleeve. The rear side of the drop-spindle, 31, is provided with teeth, 37, adapted to be engaged by a dog, 38, through an opening 75 formed in the wall of the sleeve, 33, said dog forming one arm of an angle-lever. The other arm, 39, of said angle-lever projects into the path of the sleeve, 18, and is adapted to be engaged thereby when said sleeve is depressed to hold the dog, 38, out of engagement with the teeth, 37. A coil-spring, 40, serves to force the dog, 38, into engagement with said teeth, 37, when the angle-lever is released by the upward movement of the sleeve, 18. After the drop-spindle, 31, has been raised or partly raised, it is thus prevented by the dog, 38, from again resuming its depressed position until after the thread is released from the locking mechanism by the downward movement of the sleeve, 18.

The operation of the thread-locking mechanism is as follows: The machine being stopped at the completion of a sewing operation, with the needle withdrawn from the work, 41, the disk, 3, is forced away from the disk, 2, to release the work, which operation, by rocking the angle-lever, 4-6, moves the hook, 24, to release the sleeve, 18, which instantly is forced upward by the coil-spring, 19, to lock the thread as above described. The work is then drawn out, causing a pull upon the threads, 11 and 11^a, which takes up the slack of the loop, 34, drawing upward the drop-spindle, 31, to the position shown in Fig. 3, in which position it is supported by the dog, 38. This forms stretches, 11^b, of these threads between the work and the needle and looper respectively, 110 which stretches are severed, leaving free ends of the threads sufficient for starting the next sewing operation. When the machine is again started, the first forward movement of the needle-bar causes the cam, 28, to engage the cam, 29, and force the sleeve, 18, downward until the shoulder, 27, automatically interlocks with the hook, 24, which downward movement of the sleeve also releases the dog, 38, as above described, 120 permitting the spindle, 31 to drop down to its depressed position as shown in Figs. 2 and 4.

What I claim as new and desire to secure by Letters Patent is—

1. In a machine of the class described, and in combination, stitch-forming mechanism; a presser engageable with the work; a thread-locking device; mechanism for simultaneously imparting to the presser a 130

work-releasing movement and to the thread-locking device a thread-locking movement; and a yielding take-up for the thread between the thread-locking device and the 5 stitch-forming mechanism.

2. In a machine of the class described, and in combination, stitch-forming mechanism; a presser engageable with the work; a pair of telescopically arranged members provided with thread-apertures adapted to aline with one another in one position of said members; a spring adapted to telescopically move one of said members relatively to the other to disaline said apertures; 10 a detent for holding said spring-actuated member with said apertures alined; and means whereby said detent is automatically released by a work-releasing movement of said presser.

20 3. In a machine of the class described, and in combination, stitch-forming mechanism; a presser engageable with the work; a pair of telescopically arranged members provided with thread apertures adapted to aline 25 with one another in one position of said members; means for supporting said members with said apertures alined, while the presser is in engagement with the work; and means for automatically moving one of 30 said members relatively to the other to disaline said apertures simultaneously with a work-releasing movement of the presser.

4. In a machine of the class described, and in combination, stitch-forming mechanism; an automatically actuated thread-locking device; a yielding movable take-up for the thread between the thread-locking device and the stitch-forming mechanism; a yielding dog for preventing a return 40 movement of said take-up; and means for automatically releasing said dog by an unlocking movement of said thread-locking device.

5. In a machine of the class described, and in combination, stitch-forming mechanism; a thread-locking device comprising an apertured spindle and a sleeve telescopically mounted upon said spindle and provided with an aperture adapted in one position to 50 aline with the aperture in the spindle, said alined apertures being adapted to freely receive the thread; a spring tending to move said sleeve to disaline said apertures; an automatically locking hook engageable with 55 said sleeve to hold it in a position with said apertures alined; and means whereby said hook is automatically released at certain times.

6. In a machine of the class described, and in combination, stitch-forming mechanism; a thread-locking device comprising an apertured spindle and a sleeve telescopically mounted upon said spindle and provided with an aperture adapted in one position to 60 aline with the aperture in the spindle, said

alined apertures being adapted to freely receive the thread; a spring tending to move said sleeve to disaline said apertures; an automatically locking hook engageable with said sleeve to hold it in a position with said 70 apertures alined; means whereby said hook is automatically released at certain times; a yielding take-up for the thread between the thread-locking device and the stitch-forming mechanism; and a yielding dog for 75 preventing a return movement of the take-up, said dog being held out of operative position by said sleeve while the sleeve is engaged by said hook and automatically engaging the take-up when released by the 80 thread-locking movement of said sleeve.

7. In a machine of the class described, and in combination, stitch-forming mechanism having a movable element carrying a cam; a thread-locking device adapted to be automatically opened by movement of said cam; an automatically engaging detent for holding said thread-locking device open; means for automatically releasing said detent at certain times; and means for automatically 90 closing the thread-locking device when released from the detent.

8. In a machine of the class described, and in combination, stitch-forming mechanism; a pair of work-holding-and-feeding disks; a lever upon one arm of which one of said disks is mounted; a spring engaging the other arm of said lever tending to force said disks together; an automatically closing thread-locking device; and a detent for holding the thread-locking device open adapted to be engaged and released by movement of the spring-engaged arm of said lever. 95

9. In a machine of the class described, and in combination, stitch-forming mechanism including a needle carried by a reciprocating needle-bar; a cam mounted upon said needle-bar; a pair of work-holding-and-feeding disks; a lever upon one arm of which one of said disks is mounted; a 105 spring engaging the other arm of said lever tending to force said disks together; a thread-locking device having a movable member whereby it is opened and closed; a spring engageable with said movable member tending to close said thread-locking device; a projection on said movable member adapted to be engaged by said cam to automatically open the thread-locking device; and a detent automatically engageable with 110 said movable member to hold the thread-locking device open and adapted to be engaged and released by movement of the 115 spring-engaged arm of said lever.

10. In a machine of the class described, and in combination, stitch-forming mechanism including a needle carried by a reciprocating needle-bar; a cam mounted upon said needle-bar; a pair of work-holding-and-feeding disks; a lever upon one arm of 125

which one of said disks is mounted; a spring engaging the other arm of said lever tending to force said disks together; a thread-locking device having a movable member whereby it is opened and closed; a spring engageable with said movable member tending to close said thread-locking device; a projection on said movable member adapted to be engaged by said cam to automatically 10 open the thread-locking device; a detent automatically engageable with said movable member to hold the thread-locking device open and adapted to be engaged and released by movement of the spring-engaged 15 arm of said lever; and a yielding take-up for the thread between said thread-locking device and the stitch-forming mechanism.

11. A thread-locking device comprising

in combination, an apertured spindle having an overhanging head formed with a 20 flange depending approximately to the line of said aperture; a sleeve slidably mounted on said spindle and provided with an aperture adapted in one position of the sleeve to align with said spindle-aperture; a spring 25 tending to force the apertured portion of said sleeve into the space between the upper end of the spindle and said flange; and a detent for holding the sleeve with its aperture aligned with the aperture in the spindle. 30

In testimony whereof, I have hereunto set my hand this 11th day of October, 1913.

FRANK J. KAUFMANN.
